UNITED STATES PATENT OFFICE.

ALEX. BERNSTEIN, OF BOSTON, MASSACHUSETTS.

ELECTRIC SWITCH OR CIRCUIT CONTROLLER.

SPECIFICATION forming part of Letters Patent No. 284,715, dated September 11, 1883.

Application filed May 21, 1883. (No model.)

To all whom it may concern:

Be it known that I, ALEX. BERNSTEIN, of Boston, in the county of Suffolk and State of Massachusetts, have invented certain Improvements in Electric Switches or Circuit Controllers, of which the following is a specification.

This invention relates to electric switches, circuit controllers, or circuit changers. Its object is the construction of an electric-circuit controlling switch adapted particularly and especially for use in connection with incandescent electric lamps, but which is suitable and equally applicable for use with other systems of electric lighting, or, in fact, with electric circuits of any description.

The especial form of circuit-controller which I have devised and shall hereinafter describe has been designed, mainly, for the purpose of preventing or avoiding the arcs between the two separated portions of the circuit, which invariably occur when an electric circuit in which strong currents circulate is broken. These arcs are constituted under the same conditions in which they are purposely produced in the so-called "electric-arc lamps." The two ends of the circuit, which normally form a perfect contact with one another, are gradually separated; and since the separation is gradual and is not suddenly effected a partial contact is sometimes still maintained for an instant at the point of separation, and the consequence is the heating of the contact-surfaces and of the air between them. This heated air supports the existence of the arc, being aided therein by minute portions of the volatilized substance of the two contact-pieces, until the distance between the original two portions of the circuit is too large in proportion to the electro-motive force of the passing current. When this occurs in an electric switch or circuit changer, the surfaces of the two contact-pieces become slightly oxidized, and when the switch is again closed the connection is frequently found to be imperfect.

Experience has demonstrated that in order to avoid the formation of arcs as much as possible, and thus obviate these defects at their source, it is desirable to open the circuit in an extremely quick and prompt manner, as when so accomplished the air between the two contact-surfaces has not time to be sufficiently

heated. I have also found that when switches or circuit-changers are employed with incandescent electric lamps another difficulty arises. In this and similar cases these switches must necessarily be handled by persons unacquainted with the operation of electric instruments, and instead of breaking the circuit entirely this operation is very imperfectly effected, a defective contact being often made or retained when the circuit is supposed to be completely broken. This is due to the action of the manipulator, who continues to hold the hands, with which such switches are generally provided, in a half-way position. Under such circumstances the contact-pieces are liable to burn off, or in other ways to sustain damage. In order to avoid these difficulties in operation, and at the same time to prevent the formation of arcs, my invention consists, broadly, in a switch in which the circuit is broken by mechanical force, independent of the volition of the operator. This force is stored up by the act of closing the circuit, and is expended or utilized in opening the circuit. To speak more specifically, I use for this purpose a spring which is compressed by the operation of closing the circuit, and which, when released, opens the circuit quickly, promptly, and effectively, and by means of devices which are beyond the control of the manipulator.

I shall now proceed to describe the various details of this switch, reference being made to the drawings which accompany and illustrate this specification.

Figure 1 is a sectional elevation of my improved circuit-controller, showing the circuit open. Fig. 2 is a similar sectional drawing, showing the circuit closed. Fig. 3 represents a side elevation, in which but one contact-spring is used, the metal portion of the circuit-controller itself being employed as the opposite contact-face. Fig. 4 is a detail of one of the operating parts. Fig. 5 represents a modification of Fig. 3, adapted, especially, for use in circuits traversed by electric currents of great strength or high intensity; and Fig. 6 is a detail of the same.

In Figs. 1 and 2 the apparatus is represented as being attached to any suitable base, frame, or piece of non-conducting material, B. Attached to the opposite side of such insulated

piece are two contact springs or plates, *a* and *b*, and to these contact-springs the circuit-wires *w* and *w'* are attached. *w* represents in Fig. 1 a return-wire, and the wires *w'* and *w*' are supposed to loop into any suitable apparatus by means of the binding-screws 1 and 2. 5 3 and 4 are the main binding-screws or circuit terminals, by which the entire device may be connected with the main circuit. The switch itself consists, mainly, of three pieces—the two shafts or spindles *x* and *D* and the socket or inclosing-case *A*, the said socket inclosing the operating parts and containing suitable bearings, wherein the shafts are adapted to slide. 10 15 All these parts are made of metal, and thus adapted to conduct electricity. The inner end, *d*, of the spindle or shaft *x* is tapered off, and adapted, when the said shaft is pushed in by means of the button *C*, to slide and fit 20 between the two contact springs or plates *a* and *b*, and in this position, as shown in Fig. 2, the circuit is closed. This shaft has two collars, *c* and *z*, and as the inner one, *c*, is larger in diameter than the second one, the projection *i* of the large collar over the diameter 25 of the small one, and the projection *i'* between the small collar *z* and the shaft *x*, limit the sliding motion of the shaft, as will be hereinafter described. The inner side of the collar *c* 30 presses against the spiral spring *f*, which is inclosed in the chamber *E* of the case *A*, between the base of the said chamber and the said inner side of the collar *c*. This spiral spring is shown in Fig. 1 as being expanded, 35 and thus with a slight but constant pressure holding the shaft away from the circuit-closing springs; but as represented in Fig. 2 it is compressed or in tension by the forward position of the shaft. The said shaft *x* is supported 40 in place by the bearing of the circumferential surface of the larger collar *c* against the internal surface of the casing-chamber *E*, and also by the bearing of its inner end in the hole *n*, by which the base of the said chamber is per- 45 forated. The purpose of the other shaft, *D*, which crosses the shaft *x* at right angles, is to control and regulate the motion of the said first shaft, *x*. The shaft *D* slides in the chamber *F*, which crosses the chamber *E* also at right 50 angles. At one end of the chamber *F* the shaft *D* is supported in the bearing *G*, and at the other end a small hole is bored, through which the smaller part of the said shaft slides. The same shaft, *D*, at its lower end, is formed with 55 a shoulder, *y*, and from thence to the extreme end is much smaller in diameter, the small part *g* being surrounded by a spiral spring, *k*, which, like the spring *f* of the other shaft, serves to press the shaft outwardly. The shaft 60 at its upper end is provided with a press-button, *P*, and is, furthermore, perforated at its center with an oval hole, *m*. The specific construction of this shaft is clearly shown in Fig. 4, wherein *D* represents the main body of the 65 spindle, provided at the top by the button *P*, extending below into the smaller spindle *g* and pierced through its center by the oval hole *m*.

This hole is large enough for the collar *z* to slide through easily. The spiral spring *k*, which surrounds the extension *g*, fills up the lower part of the chamber or cavity *F*, and tends always to press the lower part of the interior of the hole *m* against the shaft *x*. 70

I will now describe the action of the switch. When the circuit is open and the position of the parts is as indicated in Fig. 1, the two contact-springs *a* and *b* have no electrical connection with one another, the circuit being consequently open between them. The end *d* of the spindle or shaft *x*, which, when pushed in, tends to connect these springs through its substance, is withdrawn from them by the resiliency or expansibility of the spiral spring *f*. It is prevented, however, from moving any farther away from the contact-springs or from being withdrawn any farther than is desired by means of the engagement of the flange or projection *i* of the large collar *c*, when forced outward by the spiral spring *f*, with the edge of the oval hole *m* in the cross-shaft *D*, the 80 spring *f*, when expanded, being still capable of exerting a slight outward pressure on the said collar. The spiral spring in the cross-chamber *F*, which acts upon the other shaft or spindle, *D*, is, however, at this time in a state of tension, pressing the said shaft upward, and thus maintaining the lower edge of hole *m* in contact with the shoulder or projection of the collar *c*. If, now, the circuit-springs *a* and *b* are to be brought into contact, and the circuit 90 is to be thereby closed, the button *C* must be pressed, and the force exerted by such pressure has several results: First, the small end *d* is thrust between the contact-springs *a* and *b*, electrically uniting them; second, the spiral 95 spring *f* is compressed between the lower edge of the collar *c* and the bottom of the chamber in which such collar works; third, the small collar *z* is pushed out of the oval hole *m* of the other cross-shaft, *D*, its place being taken by 100 the much smaller shank of the shaft *x*. This relieves the pressure of the shoulder *y* of the cross-shaft *D* upon the spiral spring *k*, and by virtue of the resiliency of said spring the shaft *D* is forced upward, allowing the lower surface of the hole *m* to engage with the shoulder *i'* of the small collar *z* of the shaft *x*, the entire 105 result of the complex operation being to close the circuit between the contact-springs, to compress the spiral spring *f*, and thus store up energy, and the establishment of an engagement 110 between the shoulder *i'* of the collar *z* and the lower edge of the hole *m* through the cross-shaft *c*, whereby the spiral spring *f* is prevented from immediately expanding, and thus 115 again opening the circuit before such opening is desired. This condition is clearly shown in Fig. 2, wherein the spring *f* is shown as compressed and as being retained in a compressed condition by the contact of the lower edge of 120 the hole *m* with the shoulder *i'* of the collar *z*. It is perfectly evident that the circuit cannot 125 now be broken between the contact springs or plates *a* and *b* unless the engagement between 130

the small collar *z* and the lower edge of the hole *m* be first disestablished, permitting the spiral spring *f*, by virtue of its resiliency, to throw the shaft *x* outwardly, thus withdrawing the small end *d* from the said contact-spring. Let it now be supposed that the circuit is to be again opened or changed. All that is requisite is to exert a pressure upon the button *P* of the shaft *D*, and thus to compress the spring *k*. This brings the lower edge of the hole *m* below the shoulder *i* of the small collar *z*, permitting the said collar to pass into the said hole under the expanding influence of the spring *f*, of course contemporaneously withdrawing the small end *d* of the shaft *x* from the contact-springs and opening the circuit. This backward motion is accomplished in a very quick, positive, and efficient manner under the influence of the expansion of the spiral spring *f*, and terminates as positively as soon as the shaft comes into the position shown in Fig. 1. It is therefore obvious that the object for which I have invented this switch or circuit-controller is fully accomplished. The breaking of the circuit is done with the utmost rapidity, and the operation itself once started is not in any manner controlled by the will or by the hesitation of the manipulator, so that partial and objectionable contacts are entirely avoided.

I may of course, if I so desire, instead of using two contact-springs, *a* and *b*, employ but one, *a*, utilizing the metal part of the shaft *x* and the contiguous parts thereof as the complementary electrode of the circuit, the small end *d* of the said shaft *x* being in this case adapted to come into contact with the single contact spring or plate *a*, as shown in Fig. 3. In this case one of the wires, *w*, is fastened to any suitable portion of the body of the instrument by a suitable screw, *s*, or in any other well-understood manner. Fig. 3 also represents the appearance of the entire instrument. Although the modification thus described is perfectly adapted for use in connection with currents of low tension, such as those employed in incandescent electric lighting, and although such use is perfectly safe and innocuous in such a connection, it is possible that when used in connection with wires or circuits conveying high tension or abnormally-strong currents, a shock might be given to the manipulator. To prevent any such contingency I provide a button or knob, *R*, of suitable non-conducting material, and affix the same permanently to the metal buttons or handles *C* and *P*, as shown in Fig. 5.

It will be seen that since all that is requisite, in order to close the circuit is a pressure upon the button *C*, and since, furthermore, all that is requisite in order to open the circuit is a similar pressure upon the other button, *P*, the entire circuit-controlling device is not only simple in its construction, but the method of operation is well adapted to be put into the hands of inexperienced persons for use.

Although I have shown and described my invention as applied to establishing and break-

ing a circuit, it is evident that it may be equally well used by those skilled in the art to change the direction of the circuit, and thus 70 to switch an electric current in another direction. I desire also to state that I do not confine myself to any specific size, and that my apparatus may be greatly enlarged or diminished in size without in any way affecting its 75 efficiency.

Having now fully described my invention, I claim—

1. A circuit-controlling switch consisting, substantially as hereinbefore described, of 80 contact plates or springs, a conducting shaft or spindle provided with a retracting-spring acting to withdraw the said shaft from the said contact-springs, means for bringing the said shaft into contact with the said contact-springs and for compressing the said retracting-spring, a device for maintaining the said contact against the expansive force of the said retracting-spring, and other means for releasing the said shaft from said maintaining devices, whereby the compressed spring may be permitted to exert its expansive force upon said shaft; and forcibly and rapidly withdraw the same from the contact-springs, for the purposes specified.

2. A circuit-controlling switch consisting, substantially as hereinbefore described, of one or more contact plates or springs, a conducting shaft or spindle provided with a retracting-spring acting to withdraw the said shaft 100 from the said contact-springs, means for bringing the said shaft into contact with the said contact spring or springs and for simultaneously compressing the said retracting-spring, and other means for maintaining the said contact against the expansive force of the said retracting-spring.

3. In a device for breaking or closing electric circuits, the combination of the containing-socket, a circuit-controlling shaft sliding 110 therein, a spring adapted to exert an outward pressure on the said shaft, suitable means, as indicated, for limiting the range of outward movement of said shaft, an extension-shank and press-button attached thereto, whereby 115 the said shaft may be manipulated and advanced inwardly against the outward pressure of the spring, and an abutment adapted, when the shaft is pushed in, to compress the said spring and increase the said outward pressure, other devices for locking the said shaft in 120 position when so advanced, and means, substantially as described, for unlocking the said shaft, and for permitting it to be acted upon by the compressed spring and positively forced 125 outwardly, for the purposes specified.

4. The combination, with an electric circuit, of a controller therefor, consisting of a metal shaft or spindle adapted to complete or interrupt the said circuit by making or breaking 130 contact with contact springs or plates attached thereto, the said shaft being provided with a retracting-spring with shoulders or abutments, and with means for bringing it into contact with

the said contact-plates and for compressing the retracting-spring, together with a locking-shaft, also provided with a retracting-spring with a shank and press-button, whereby the 5 same may be compressed, and with an oval hole or slot through which the first shaft is passed, and which is adapted to engage by its lower edge the several abutments of the said first shaft, according to their respective positions, whereby the compression of the retracting-spring of the former shaft may be caused to complete the circuit and to release the retracting-spring of the locking-shaft, and whereby the compression of the spring of the locking-shaft may be caused to release the spring of 15 the former shaft and effect a sudden opening of the circuit, substantially as and for the purposes described.

5. In an electric switch or circuit controller, 20 the combination of the containing socket or chamber, a locking-shaft centrally perforated with a hole or slot, and provided with a retracting-spring and a button, whereby it may be forced inwardly against the expansive force 25 of said spring, and a circuit-controlling shaft arranged transversely to the locking-shaft and passing through the hole thereof, the said circuit-controlling shaft being provided with a retracting-spring therefor, adapted to exert 30 a force an outward pressure thereon, a button whereby it may be forced inwardly, and two collars of different diameters, forming shoulders, one of which is adapted to engage with the edge of the hole or slot of the locking- 35 shaft when the button of the circuit-controlling shaft is pressed inwardly, the other being adapted to similarly engage the said edge of the said hole when the circuit-controlling shaft, influenced by its retracting-spring, reaches its 40 extreme outward limit, substantially as hereinbefore described.

6. In an electric switch or circuit controller, 45 the combination of the locking shaft or spin-

dle, having an oval hole or slot of suitable size, with a circuit-controlling shaft or spindle 45 passing through the said hole in the locking-shaft, and having two projecting parts fixed thereon, one of which is adapted to slide in the said hole, and both forming shoulders adapted to abut against the edge of the said 50 hole, the said two shafts being transversely disposed with reference to one another, both being provided with buttons, whereby they may be pushed inwardly, and with retracting-springs adapted to exert an outward pressure, 55 whereby when the retracting-spring of the circuit-controlling shaft is compressed by the pressure of the button the retracting-spring of the locking-shaft is released, and when the retracting-spring of the locking-shaft is compressed 60 the retracting-spring of the circuit-controlling shaft is released, as described.

7. The combination of an electric -circuit controller adapted to be manually operated to close a circuit, a locking-shaft for the circuit-controller, adapted to engage therewith and to maintain it in place, a spring capable of being put in tension by the operation of closing the circuit, and adapted, upon the manual disengagement of the locking-shaft from the 70 circuit-controller, to expand and automatically open the circuit, and a second spring adapted to be put in tension by the manual disengagement of the locking-shaft, and to expand and automatically actuate the said locking-shaft 75 to lock the circuit-controller when the circuit is manually closed, substantially as described.

In testimony whereof I have signed my name to this specification, in the presence of two subscribing witnesses, this 15th day of May, A. D. 80 1883.
